(57) **CLAIM**

I claim the ornamental design for a combined refuse and recycling container, as shown.

DESCRIPTION

FIG. 1 is a top, front isometric view of the combined refuse and recycling container showing my new design.

FIG. 2 is an isometric view thereof from the bottom rear; and,

FIG. 3 is an isometric view thereof from the top front thereof with the transparent top raised slightly from the body or sidewalls.

The broken line showing of cans is included for the purpose of illustrating environment and forms no part of the claimed design.
